Primary Examiner — Elizabeth J Oswecki(74) *Attorney, Agent, or Firm* — Oblon, Spivak, McClelland, Maier & Neustadt, L.L.P.(57) **CLAIM**

The ornamental design for a chamber of charged particle beam drawing apparatus, as shown and described.

DESCRIPTION

FIG. 1 is a top perspective view of a chamber of charged particle beam drawing apparatus showing our new design;
 FIG. 2 is a bottom perspective view thereof;
 FIG. 3 is a front view thereof;
 FIG. 4 is a right side view thereof, the left side view being a mirror image;
 FIG. 5 is a top plan view thereof;
 FIG. 6 is a bottom plan view thereof;
 FIG. 7 is a cross sectional view taken along line 7-7 in FIG. 3; and,
 FIG. 8 is a cross sectional view taken along line 8-8 in FIG. 3.
